DESIGN FOR A HEATER

Harold E. Wilber, Noblesville, Ind., and Russell E. Kemp, Dayton, Ohio, assignors to Wilkemp Industries, Fishers, Ind., a copartnership of Indiana

Application December 26, 1946, Serial No. 135,766

Term of patent 3½ years

(Cl. D81—10)

To all whom it may concern:

Be it known that we, Russell E. Kemp and Harold E. Wilber, citizens of the United States, residing at Dayton, county of Montgomery, and State of Ohio, and Noblesville, county of Hamilton, and State of Indiana, respectively, have invented a new, original, and ornamental Design for a Heater, of which the following is a specification, reference being had to the accompanying drawing, forming part thereof.

Fig. 1 is a front elevational view of a heater embodying our new design; and

Fig. 2 is a top plan view of the heater.

Fig. 3 is a horizontal sectional view taken substantially on the line 3—3 of Fig. 1.

We claim:

The ornamental design for a heater, as shown.

HAROLD E. WILBER.
